(57) **CLAIM**

The ornamental design for a charge cube, as shown and described.

DESCRIPTION

FIG. 1 is a left side elevational view of a charge cube showing my new design, a right side being a mirror image thereof.

FIG. 2 is a front elevational view thereof;

FIG. 3 is a rear elevational view thereof;

FIG. 4 is a top plan view thereof;

FIG. 5 is a bottom plan view thereof; and,

FIG. 6 is a perspective view thereof.

The broken lines shown in the drawings are included for the purpose of illustrating environmental structure and form no part of the claimed design.

1 Claim, 2 Drawing Sheets
